UNITED STATES PATENT OFFICE.

WILLIAM J. P. MOORE, OF NEW YORK, N. Y.

DESIGN FOR AN AUTOMOBILE-BODY.

53,340.

Specification for Design.

Patented May 20, 1919.

Application filed March 7, 1917. Serial No. 153,204. Term of patent 7 years.

To all whom it may concern:

Be it known that I, WILLIAM J. P. MOORE, a citizen of the United States, and resident of New York, in the county of New York and State of New York, have invented a new, original, and ornamental Design for Automobile-Bodies, of which the following is a specification, reference being had thereto to the accompanying drawing.

Figure 1 is a side elevation of an automobile body showing my new design;

Fig. 2 is a top plan view of the same.

I claim:

The ornamental design for an automobile body, as shown.

In testimony whereof I hereunto affix my signature.

WILLIAM J. P. MOORE.
